ATTORNEY

UNITED STATES PATENT OFFICE.

JOSEPH V. TOBIN, JR., OF WISSAHICKON, PENNSYLVANIA.

SLED BRAKE.

Application filed May 10, 1926. Serial No. 108,098.

This invention relates to brakes primarily applicable upon sleds and other devices capable of travel upon snow and ice.

An object of the invention embodies a braking element carried by the sled or sleigh which may be moved to an active position to engage the surface of the snow or ice to check the velocity and acceleration of the sled.

10 More specifically stated, retractile means is combined with the braking element to normally hold the latter in an inactive position free from the snow or ice upon which the sled travels.

15 With the above and other objects in view, the invention further includes the following novel features and details of construction, to be hereinafter more fully described, illustrated in the accompanying drawing and 20 pointed out in the appended claims.

In the drawing:

Figure 1 is a side elevation of a sled with the present invention applied and used in conjunction therewith;

25 Figure 2 is a sectional view taken on the line 2—2 of Figure 1;

Figures 3 and 4 are sectional views taken on the lines 3—3 and 4—4 of Figure 2.

Referring to the drawings in detail, 30 wherein like characters of reference denote corresponding parts, the reference character 10 indicates the usual and conventional form of sled, illustrated to bring about the novel advantages of the above entitled invention when applied and used in conjunction therewith.

The invention embodies a shaft 11, preferably rectangular in cross section for an appreciable portion of its length. The ends 40 of said shaft are fitted and received within correspondingly shaped cut out portions provided in the legs or standards for the sled runners.

Spaced companion disk members 12 and 45 13 respectively are eccentrically mounted upon the rectangular portion of the shaft 11 and adjacent one end thereof. The inner side of the disk surrounding the junctures therefor upon the shaft provide enlarged or 50 frusto-conical shaped portions 14, the purpose of which will be readily apparent. The back portion of the shaft 11 between the companion disks 12 and 13 is rounded cylindrical in cross section.

Rotatably and eccentrically mounted upon the rounded or cylindrical portion of the shaft is a braking element in the form of a drum 15. Spaced brake fingers or blades 16 radiate from the periphery of the drum and converge forwardly throughout the 60 major portions of their lengths.

The companion disk 13 provides an arcuate shaped slot or cut-out portion 17 through which an outwardly extending operating handle 18 protrudes from the adjacent side of the drum.

The remaining disk 12 carries a retractile spring 19 upon its inner side and connected with the drum 15 to normally hold and sustain the latter in an inoperative position.

Manifestly a downward pressure exerted upon the handle 18 within the arcuate shaped cut-out portion 17 in the disk 13 will rock the drum 15 upon the cylindrical portion of the shaft 11 to engage the brake fingers 16 with the surface of the snow and ice over which the sled travels.

Although I have shown, described and illustrated the invention as applied and used upon sleds, it is obviously understood that the invention may be equally and effectually as well applied to toboggan sleds and sleighs.

The invention is susceptible of various changes in its form, proportions and minor details of construction, and the right is herein reserved to make such changes as properly fall within the scope of the appended claims.

What I claim as new is:

1. A sled brake, a shaft carried by the sled, a drum eccentrically mounted upon the shaft, disk members fixed upon the shaft, an operating handle carried by the drum for shifting the latter to an operative position, and means carried by one of the disks and connected with the drum to normally hold the latter in an inoperative position.

2. A sled brake, a shaft rectangular in configuration carried between the legs of the sled, said shaft further provides a cylindrical portion adjacent one end thereof, a drum eccentrically mounted upon the cylindrical portion of the shaft, braking fingers arranged at spaced intervals upon the periphery of the drum and converging forwardly throughout the major portions of their lengths, companion disks eccentrically

and rigidly mounted upon the rectangular portions of the shaft and upon the opposite sides of the drum, one of the disks providing an arcuate shaped cut-out portion, an operating handle carried upon the drum and protruding through the arcuate shaped cut-out portion, and a retractile spring carried

upon the inner side of the remaining disk and connected with the adjacent side of the drum to normally sustain the latter in a 10 normally inactive position.

In testimony whereof I affix my signature.

JOSEPH V. TOBIN, JR.
